UNITED STATES PATENT OFFICE.

NILS SVENSSON BÖK, OF STOCKHOLM, SWEDEN.

CENTRIFUGAL SEPARATOR.

No. 834,254.

Specification of Letters Patent.

Patented Oct. 30, 1906.

Application filed May 3, 1905. Serial No. 258,728.

To all whom it may concern:

Be it known that I, NILS SVENSSON BÖK, a subject of the King of Sweden, and a resident of Stockholm, Sweden, have invented new and useful Improvements in Centrifugal Separators, of which the following is a specification, reference being had to the drawings accompanying and forming a part hereof.

This invention relates to separators in which the matter under treatment is made to pass from the inner to the outer parts of a hollow body placed wholly or partially within the separating vessel and made in one or more pieces cut open chiefly longitudinally and having an elongated shape axially to the separating vessel; and it has for its object to so support the fixed or loose parts of the said hollow body that even with long incisions and high rotary velocities of the rotating hollow body the said parts with their high centrifugal pressure either will not at all or but slightly need strain the adjacent parts of the partition-plates inserted in the separating vessel, which partitions are already subjected to stresses from their own centrifugal forces. The need of such supports is more particularly felt when in a separating vessel of elongated shape rotating at as great a velocity as the vessel or its accompanying parts will admit it is desired for reasons connected with the conditions for a proper distribution of the matter under treatment between the partitions to so shape the said body that its own sustaining power will not even suffice to resist the stresses arising therein at a much lower number of revolutions.

The invention consists chiefly in the combination, with a distributing device of the kind set forth, of a supporting-body placed wholly or partly inside the said distributing device and having suitable projections against which the walls of the distributing device or projections thereon bear in such a manner that the centrifugal forces arising in the said distributing device during the rotation of the bowl will be wholly or partly taken up by the said supporting-body.

In the accompanying drawings I have shown some embodiments of my invention.

Figure 1 shows a central vertical section of a part of a centrifugal separating-bowl and a device according to the present invention. Fig. 2 is a horizontal section on line A B in Fig. 1. Fig. 3 shows a vertical section of a second constructional form. Fig. 4 is a horizontal section on line C D of Fig. 3. Fig. 5 is a vertical

section of a third constructional form, and Fig. 6 is a horizontal section on line E F in Fig. 5.

Like reference-numbers indicate same or corresponding parts throughout all the figures.

Referring to Figs. 1 and 2, 1 represents a well-known central pipe of an Alpha-Laval separator, 3 the wings of the said central pipe, and 2 longitudinal channels in the said wings. The sustaining-body 4 5 6 here is composed of a tube 4 of square section, provided at each corner with a radially-projecting vane 5, the outer edge of which is provided with a longitudinal flange 6, so shaped as to form with the vane 5 in cross-section a T, the axially-facing parts of which form abutments for the walls 3, forming the passages 2. When, as in Figs. 1 and 2, the spider-vanes are in one piece, both with the cylindrical part 1 of the center tube and with the so-called "slime-cup" 7, the sustaining-body 4 5 6 is introduced from below into its position in the spider through the open bottom of the slime-cup and up through the apertures 9, made in the roof 8 of the slime-cup and corresponding to the vaned shape of the sustaining-body. The matter to be treated is admitted, as usual, through the upper part 1 of the center tube and is conducted through the latter down into the slime-cup 7, whence it rises into the supply-passages 2. The abutment-flanges 6 are arranged so as to leave at the bearing edge a passage for the matter under treatment admitted from the axial supply-passage 2 as it is made to flow out of the apertures (15 and 22, respectively) at the abutment-surfaces and distribute over all the feed-sections situated along the flange 6 between adjoining edges of the partitions 10. A hook 18, secured radially in the upper part of the slime-cup, supports the bottom end of the sustaining-body 4 5 6, thus keeping it in place axially, while the square part 4 of the body 4 5 6 bears with its outer sides against the inner parts of the passage-walls 3.

Fig. 3 represents in a vertical section axially and Fig. 4 in a horizontal section on line C D of Fig. 3 another spider device provided with supports according to the present invention.

In Figs. 3 and 4 the sustaining-body 4 5 6 ties together a spider 17 12 3, formed of four similar parts. The function and support of said four spider parts 17 12 3 is here effected by the short vanes 5, projecting from the

- square tube 4, sustaining by means of the axially-facing sides of a longitudinal flange 6 the swelled ends 12 of the spider-wall 17, which is here somewhat strengthened. The 5 spider-walls 3, projecting from the walls 17, form the axial supply-passages 2. In Fig. 4 (on the right) the outer parts of the walls 3 approach each other in such a manner as to provide a radial distributing-passage 13, offering sufficient resistance to the matter under 10 treatment, which is here distributed to the adjacent feed-apertures between the edges of the partitions 19. At the bottom of Fig. 4 the sustaining-body 4 5 6 is also shown to 15 carry a vane 16, projecting radially from the flange 6 through the passage 2 and terminating in a cylindrical bead 14, forming, with the insides of the converging parts of the walls 3, the passages 15.
- 20 In Figs. 3 and 4 the square part 4 of the sustaining-body is built together with both the center tube 1, serving as inlet for the matter to be treated, and with the slime-cup 7, which has at the top a passage 9 for the matter supplied to the axial passage 2. The 25 four loose spider-walls 17 12 3, forming the axial passages 2, are held depressed by means of a nut 11 or corresponding device screwed onto the cylindrical center tube 1, so as to 30 bear with their bottom ends on the flat roof 8 of the slime-cup 7, bounding the passages 9 made therein.
- Fig. 5 shows in a vertical section axially and Fig. 6 in a horizontal section on line E F 35 of Fig. 5 a modified arrangement of the device shown in Figs. 3 and 4. Each of the four parts constituting the spider 17 12 3 is built together with one part of the cylindrical inlet 1, which is likewise made in four parts. 40 The sustaining device 4 5 6, acting in the same manner as in Figs. 3 and 4, is here built together with the slime-cup 7 only. The nut 11 or equivalent part screwed onto the cylindrical portion of the spider here serves to bind 45 together centrally the four sections of the spider, so as to allow of their ready insertion from above around the sustaining-body 4 5 6. The spider is depressed into place, with its lower end bearing on the roof 8 of the slime- 50 cup 7 by means of a cylindrical spiral spring 20, surrounding the cylindrical portion 1 and compressed by the separator-cover 21, which is screwed on.
- In Fig. 6 at the right the distributing radial 55 channel-section 13 reaches clear into the recessed edges of the conical partitions. A portion of the wall 3 of the axial passage 2, which is here considerably inclined to radius, under influence of the centrifugal force finds 60 some support from the recessed edges of the partitions. In very large or quickly-revolving separators, where the passages 2 may be of large dimensions, the portions of the walls 3 inclining considerably to the radius may 65 create severe stresses in the central portions of the partitions. In order to diminish these stresses, supports may be provided also for these inclined wall portions 3. (See Fig. 6, at the bottom.) From the supporting-flange 6 a vane 16 projects radially through 70 the axial supply-passage 2, terminating in another longitudinal flange 14, and against the axially-facing sides of this flange the ends of the inclined passage-walls 3 find support. Passages for the matter under treatment are 75 arranged at the place of support by means of recesses 15 and 22 at the edges, as in Figs. 1 and 2. The number of supply-passages 2 evidently can vary. With three passages a triangular and with, for instance, five passages a five-cornered sustaining-body is used, so as to subject the sustaining-walls 4 of the sustaining-body chiefly to tensile stresses. This evidently does not exclude the use of an 80 annular body of sufficient strength for the purpose. The sustaining-body need not axially be made in one piece. The walls of the spider-vanes evidently may also be supported by means of two or more short sustaining-bodies situated along the axis and made of 85 sectional shapes similar to those shown in the above. Moreover, the sustaining-body may, as shown in Fig. 1, pass with bottom part more or less deeply into the slime-cup, where its projecting vanes may serve to carry the 90 entering matter along and set it into full rotation. All the devices shown combine great resisting power to centrifugal influences with facility of cleaning, owing to the ease with which the construction can be 95 taken apart. By this supporting device one of the obstacles is overcome which have hitherto prevented the practical use of high 100 rotary velocities in separators when a thorough distribution of the matter under treatment to all the separating-sections is to take 105 place. This applies in a still higher degree where a great rotary velocity is combined with an elongated shape of the separating vessel.
- Having now described my invention, what I claim as new, and desire to secure by Letters Patent, is—
1. The combination with a centrifugal separating-bowl and an orificed distributing device therein, of a supporting-body placed inside the said distributing device and having projections provided with bearing-surfaces facing the axis of the bowl, the distributing device bearing against the said surfaces, substantially as and for the purpose set forth. 115
2. The combination with a centrifugal separating-bowl and an orificed distributing device therein, of a hollow supporting-body placed inside the said distributing device and having projections extending through the orifices of the distributing device, the said projections having abutment-flanges engaging by surfaces facing the axis of the bowl the outer edges of the walls of the distributing 120 130

device, substantially as and for the purpose set forth.

3. The combination with a centrifugal separating-bowl and an orificed distributing device therein, of a supporting-body of polygonal horizontal section placed inside the said distributing device and having projections provided with bearing-surfaces facing the axis of the bowl, the distributing device bearing against the said surfaces, substantially as and for the purpose set forth.

4. The combination with a centrifugal separating-bowl and a distributing device therein divided axially in several parts, of a supporting-body placed inside the said distributing device and having projections extending outwardly between the said parts of the distributing device, the said projections having bearing-surfaces facing the axis of the bowl, the said parts of the distributing device

bearing against the said surfaces, substantially as and for the purpose set forth.

5. The combination with a centrifugal separating-bowl and an orificed distributing device therein composed of several parts, of a supporting-body inside the same having radial projections, the latter having abutment-flanges holding together the said parts of the distributing device and other abutments engaging the outer edges of the walls of the distributing device, substantially as and for the purpose set forth. 25 30

In testimony whereof I have signed my name to this specification in the presence of two subscribing witnesses.
